UNITED STATES PATENT OFFICE.

MAURICE O'B. HALLOWELL, OF CONSHOHOCKEN, PENNSYLVANIA,
ASSIGNOR TO J. ELLWOOD LEE COMPANY, OF CONSHOHOCKEN,
PENNSYLVANIA, A CORPORATION OF PENNSYLVANIA.

ADJUSTABLE TRUSS.

SPECIFICATION forming part of Letters Patent No. 758,440, dated April 26, 1904.

Application filed November 17, 1903. Serial No. 181,526. (No model.)

To all whom it may concern:

Be it known that I, MAURICE O'B. HALLOWELL, a citizen of the United States of America, residing in Conshohocken, in the county of Montgomery, State of Pennsylvania, (having a post-office address at said Conshohocken, Pennsylvania,) have invented an Improved Adjustable Truss, of which the following is a specification.

10 The object of this invention is to improve the construction of trusses so that the pad may be readily and accurately adjusted with relation to the spring to cause the truss to fit the wearer comfortably and properly in any desired position.

15 In the accompanying drawings, Figure 1 is a back view of the pad and a portion of the spring of a truss. Fig. 2 is an edge view thereof. Fig. 3 is a sectional view with the pad removed. Fig. 4 is a view of the clamp detached, and Fig. 5 is a longitudinal central section.

20 According to this invention I fasten to the spring S a socket s, in which I form a slot O. A bifurcated plug P is adapted to be held in place in the socket s by a lateral screw s', which passes freely through the slot O and is threaded into the bifurcation a and bears at its end against the bifurcation b, so that by 25 turning this screw the bifurcations will be spread apart to cause them to tightly grip the interior walls of the socket. The slot O is through a substantial half of the socket and allows the screw s' and plug to be moved 30 through a considerable angle for adjustment. The outer end of the plug P is flattened and provided with a toothed gripping-surface engaging a like surface on the end of a rod R, a clamping-screw s² being employed to lock 35 the two surfaces together in their adjusted positions.

The pad 12 is provided with a recess in its rear to receive the clamp C. A plate 13 carries on its under side the clamp and is itself

secured to the pad by screws or otherwise. 45 The clamp C consists of a stationary plate 14, secured to the plate 13, and a plate 15, hinged to two depending lugs 66 from the stationary plate 14. A shouldered screw 7, passing freely through the cover-plate and stationary plate 50 14, is threaded into the hinged plate 15. Both stationary and hinged plates are provided with circular openings $\alpha\alpha$, on the edges of which the spherical end E of the rod R rests and against which spherical end they may be 55 clamped by the screw 7. By these adjustments the pad and rod R may be radially adjusted with relation to the plug and spring, the pad may be completely rotated on the ball E with relation to the rod, plug, and spring, 60 and the pad, rod, and plug may be partially rotated in the socket S, making an adjustment that can readily be made by an attendant or by the wearer to secure a comfortably-fitting truss and one at the same time adapted to exert 65 pressure at the right spot and in the proper direction and usable on either the right or the left side of the wearer.

I claim as my invention—

1. A truss, comprising a spring and a pad, 70 a cover-plate having a plain surface, a plate secured to the under side of said cover-plate having downwardly-projecting lugs at one end and a circular recess, a plate with a similar recess hinged on said lugs, a single screw passing through the cover-plate and taking into the free end of the hinged plate and a rod with a ball at its end fitted into said circular recesses, substantially as described.

2. A truss, having a spring and a pad, a 80 socket secured to the spring and slotted through part of its wall, a bifurcated plug, adapted to fit into said socket, a screw passing through the slit in the socket and threaded into one bifurcation, whereby the bifurcations 85 can be spread apart to clamp the plug in the socket, substantially as described.

3. A truss, comprising a pad, a clamp and

a ball-ended rod adapted to be rotated completely within said clamp, in combination with a slotted socket and spring, a bifurcated plug fitting said socket and a screw to expand the 5 plug in the socket, and a pivotal clamp connecting the extremity of the plug and ball-ended rod, substantially as described.

In testimony whereof I have signed my name to this specification in the presence of two subscribing witnesses.

MAURICE O'B. HALLOWELL.
